APPARATUS FOR PERFORATING SHEET MATERIAL

George F. Wales, Kenmore, N. Y.

Application March 18, 1943, Serial No. 479,615

34 Claims. (Cl. 164—94)

This invention relates to an apparatus for punching holes at specified locations throughout the areas of sheets of material such as sheet metal, and is particularly adapted for punching the numerous rivet holes required in the thin metal panels or sheets which are used in aircraft construction to form the outer surfaces of wings, fuselages, and the like, but the invention may be applied to other uses where relatively large numbers of holes are required in panels or sheets of materials.

The main object of my invention is to provide an apparatus and method for punching holes in sheet materials which is simple in construction, economical to manufacture and use, and easily set up for use in a press.

Another object is to provide a multiple hole punching apparatus and a method of making same in which the punch carrier plate may be used as a drill jig for drilling the die plate when both plates are assembled to the other parts of the apparatus in the same manner in which they are to be used in the punching operation.

Another object is to provide such an apparatus for the successive accommodation of any number of pairs of punch and die carrier plates, thus requiring the preparation only of the plates when new patterns of holes are to be punched.

A further object is to provide an apparatus of this nature in which so-called non-critical materials may be used for the majority of parts especially the punch carrier plates, the base plates and the support members.

Another object of this invention is to provide a single apparatus which will be capable of producing two or more different types of work-pieces.

Another object is to provide a method for making a multiple hole punching die whereby the punching devices are interchangeable from one punch carrier plate to another and also with drill bushings which are substituted for them when drilling a die plate by using each punch carrier plate as a drill jig for drilling the die apertures in coaxial alignment in its companion die plate.

Another object is to provide an apparatus and method for punching a multiplicity of holes in which the punch carrier plate is free from the pressure of punching and stripping the work from the punch and all such pressure is transmitted through the work, onto the die plate, thence through the supports to the bed of the press.

Another object is to provide means for supporting the die plates to prevent their distortion either in the drilling or punching operations.

Another object is to provide a die plate for an apparatus of this nature which is made of a metal capable of being hardened, and hardened around the die openings.

5 A further object is to provide an apparatus of this description in which the punches may be instantly serviced by lifting them freely out of their guideways in the punch carrier plates to prevent loss of time when a punch fails.

These and other objects and the several novel features of this invention are hereinafter more fully described and claimed and the preferred form of construction by which these objects are obtained, is shown in the accompanying drawings in which:

Fig. 1 is a front elevation showing a preferred design of my apparatus mounted on the stationary bed or bolster of a press and showing the reciprocating ram in its lowermost position in which the punches are driven through the work.

Fig. 2 is a plan view of the apparatus shown in Fig. 1.

Fig. 3 is a fragmentary horizontal section taken on line 3—3, Fig. 2, showing the ram in a partially elevated position, and showing locating pins for correctly positioning the punch plate and die plate relatively to each other.

30 Fig. 4 is a fragmentary horizontal section similar to Fig. 3, but showing how the holes are drilled in the die plate preparatory to the final assembly of the apparatus.

Fig. 5 shows an alternate method of drilling the punch and die plates together.

35 Fig. 6 shows how the punch plate holes are enlarged to accommodate the punch and punch guide elements.

Fig. 7 shows the die plate as it was drilled in Fig. 5 and being flame hardened before being placed in service.

40 Fig. 8 is a fragmentary sectional view of the punching mechanism in an operating position, and showing a punch unit of modified construction.

45 Fig. 9 is a fragmentary section showing a modified construction in which one of the rails is connected with the base by a bolt passing through the rail and having its head arranged in a T-shaped or undercut slot, which latter extends 50 crosswise of the base, and thus permits the rail to be shifted crosswise to permit of using die plates and punch plates of different widths.

Fig. 10 is a plan view similar to Fig. 2, but showing stop gage means of modified construction.

Fig. 11 is a sectional elevation on an enlarged scale on line 11—11, Fig. 1.

In the following description similar characters of reference indicate like parts in the several figures of the drawings.

This perforating apparatus is adapted to be used in connection with any well-known or standard punch press or similar machine which includes, among other elements, a lower supporting bed which forms the lower part of the stationary main frame of the press and on which is usually mounted a bolster plate and an upper ram which is guided upon the upper part of this main frame and movable vertically toward and from said bed.

In the space between the bolster and ram of the press, the perforating apparatus embodying my improvements is arranged and adapted to be operated by the movement of the ram toward the bed for the purpose of punching holes in the sheets of material which are fed to the perforating mechanism.

The different features of my improved perforating mechanism may be variously constructed and still embody the underlying principle of the invention.

The preferred organization of my invention which is shown in the drawings is constructed as follows:

The numeral 10 represents the stationary bed or bolster of a press and 11 the reciprocating ram of the press. The numeral 18, Figs. 1 to 4, represents a base plate resting loosely on the bed or bolster 10 of the press and 12 represents two supports having the form of bars or rails which are mounted in spaced relation on transversely opposite parts of the base plate and secured thereto by bolts 23 passing through flanges on the outer sides of these rails, as shown in Figs. 1, 2, 3 and 4. On their inner sides the two supports or rails are rabbeted to form upwardly facing shoulders, shelves or ledges 14 on which the transversely opposite edges of a die plate 13 rest and to which these parts of the die plate are secured by means of cap screws 15. Between the rails 12 the die plate 13 may be supported by brace pins 16, which may be attached to the plate 13 by means of a threaded or otherwise prepared shank 17 at the upper end of this pin secured in an opening in the die plate, as shown in Figs. 1 and 3, said pin being of the same length as the height of the ledges above the base plate 18, on which the supports are mounted. Additional supports or braces, such as bars indicated by numeral 19, may be used to support die plate 13, or any other means which provides support for the die plate while at the same time making provision for slugs punched out from the work-piece to be cleared from underneath the die plate. Each of the brace bars 19 has its lower edge resting on the base plate 18 and may be secured thereto by screws 46 or the like and has its upper edge cut away or recessed on a downwardly tapering angle first on one side of the bar, as shown at 20, and then on the other side thereof, as indicated by 21, thus staggering or alternating these recesses and providing a top surface 22 having an effective area sufficient to adequately support the die plate 13, while at the same time providing slug chutes or recesses which enables the bars to support the die plate when holes are punched close together, and provides means for the slugs from such holes to clear the lower ends of the die apertures.

While supports or rails 12 may be mounted di-

rectly upon the bolster plate 10 of a press, they are for the most part attached to a mounting or base plate 18, to provide a unitary assemblage which may be fully prepared for operation outside of the press and merely slid onto the bolster plate 10 where it is ready for immediate operation. As the supports or rails 12 may be used for different widths and lengths of die plates, such as 13, and punch plates, such as 24, the base plate 18 may be small or large to suit the size of plates 13 and 24. It might be advisable also to employ in place of plate 18 a base plate 181, Fig. 9 having T-slots running crosswise of this plate, as indicated by 25 in Fig. 9, in which case bolt heads 231 would extend into said slots 25 and nuts used for clamping the supports or rails 12 to said base plate.

Each of the supports or rails 12 is provided with an upper bearing surface 26 upon which is mounted one edge portion of a punch carrier plate 24, which carries vertically moving tubular punch guides 27, each of which is guided in holes 28 bored in this plate and held in an elevated position by light springs 29. The guide sleeves 27 are provided with vertical holes extending clear through for the accommodation of punches each of which consists of punch body 31 and punch head 32 at the upper end of the body.

In order to strip the work-piece 38 from the punch, resilient means are interposed between the underside of each punch head and the upper face of the respective guide sleeve, which means may take the form of helical springs, truncoconical washers, rubber, or any other means, such as rubber washers 33, and metal washers 34, alternating as shown in Fig. 8. Take-up washers 30 are inserted between the lowermost rubber washer and the top of the respective guide tube or sleeve 31 when the punch is new and these take-up washers may be removed as the punch wears and is ground shorter and thus prevent over-compressing the rubber washers.

Preferably the punch unit is constructed so that the height of the various punch units may be the same. This may be accomplished by having the upper end of the punch extend through its head 32 and providing a cap 300 with a central aperture into which the upper end of the punch may extend, as shown in Fig. 8. The cap also has a downwardly extending annular skirt portion 301 extending about the head. As the punch becomes shorter by grinding the lower end thereof, any washer 30 removed from its place above the upper end of the punch guide sleeve may be placed upon the head 32 of the punch and below the cap 300, thus keeping the total distance from the plate 24 to the upper end of the cap the same, regardless of the length of the punch.

The punch plate 24 is attached to supports or rails 12 by means of bolts 35, and this plate is provided with openings 36 to provide access to bolts 15, which attach the die plate to the ledge of the supports 12 below the level of the punch plate.

The organization by which this apparatus provides the simplicity of preparing the punch plate and die plate will be discussed later. For the present, let it be assumed that the plates have been prepared by forming the holes 28 in the punch plate (Fig. 6) for the punching elements in correct relation to each other as desired in the finished part. Also that the holes 47 for the bolts 35 have been drilled so that said punch plate may be bolted to the supports 12. Also let it be assumed that the die openings 37 have been drilled in plate 13 and hardened and that the bolt holes

151 for bolts 15 have been formed in the die plate. Then the manner of assembling the apparatus is as follows:

If brace pins 16 are used they are engaged with die plate 13 wherever required. If brace bars 19 are used, they are placed in position on base plate 18. The supports or rails 12 are then placed upon the base plate 18 in the approximate position to accommodate die plate 13 which is placed on the ledges 14. By shifting the die plate and rail, one relative to the other, the screws 15 will find tapped holes in the rails and may be tightened and this will clamp the die plate 13 in position where it will be resting on the brace bars 19, or pins 16. Punch plate 24 is then placed on the supports 12 and clamped by means of the screws 35.

The holes in the die plate 13, through which bolts 15 extend, are enough larger than the body of the bolt to provide easy assembly of the plate with the supports 12. The holes for bolts 35 in punch plate 24 are larger than the body of the bolt to allow the punch plate 24 to be shifted slightly to obtain proper concentric alignment of the die holes 37 with the punch guide holes 28 before being clamped tightly. This alignment is obtained by inserting locating pins 45 in the punching device holes 28 of the punch plate as substitutes for preferably three punching devices. These pins are reduced at their lower ends to form pilots 46 which just fit the respective die openings 37 in such manner that the two plates 13 and 24 may be positioned with all companion holes in concentric relation with one another. The two plates 13 and 24 are then both bolted tightly to the supports 12. Screws 15, being socket head cap-screws, are tightened by inserting a wrench through the openings 38. The locating pins 45 are then removed and the punching devices reinstated, upon which the apparatus is ready to operate.

It is taken for granted that gaging means must be used to locate the work 38 properly in the apparatus and pins 39, or a nest, may be used on the die plate for this purpose.

Another method of gaging the work properly is illustrated in Fig. 10, according to which holes 401 are formed in the work-piece, previous to the present operation and pilot pins 40 are provided on the upper faces of the brace bars. These brace bars 19 are then adjusted so that pilot pins 40 on these bars engage the holes in the work-piece when this piece is in correct relation to the punch and die units, in which case pins 39, or punch and die units, in the nest, are not used. When pins 40 are used, the brace bars are anchored against movement by screws 46 in plate 18. Obviously the locating pins may be arranged in the die plate 13, if desired.

I have shown work-piece 38 projecting in front of the apparatus. If, however, the work enters entirely into the apparatus, it may be desirable to cut out hand openings or notches like 41 to enable the operator to place the piece in position properly. Sight holes 410 may be provided in the punch plate 24 through which the gage pins 39 may be easily seen.

The preparation of the punch carrier plate 24 consists of first drilling and reaming the holes 28, wherever a hole is desired in the finished piece. The holes may be located from templates or in any other manner. After these holes have been formed and properly prepared to slidably receive sleeves or tubes 27, the holes 42 are drilled in the punch plate larger than the diameter of

the bolts 35 and this plate is then clamped tightly in place on supports 12 which are bolted to the base plate 18.

A blank die plate 13 of chrome-molybdenum steel, or other steel capable of being flame hardened, is then drilled to take the bolts 15, and this blank plate 13 is then slid onto ledges 14 and the bolts inserted through holes 36 in the punch plate and tightened by means of a socket wrench engaging the socket head screws 15.

The next step which is novel in die construction consists of inserting a drill bushing 43 in one of the punch plate openings, inserting a drill 51 in the hole of this bushing, and drilling the die hole 37, as shown in Fig. 4. The size of the drill is such as to give the proper clearance between the punch and the die hole. All punching operations require that the die hole be larger than the punch by from 5% to 25% of the thickness of the material. The hole 44 in the drill bushing will therefore be the size of the required die hole and not the punch size. As an example, if the punch is .125 in diameter and the metal to be punched .050 thick, the drill size will be 10% of .050 larger, or .130 in diameter. When drilling die plate 13 by this means, the support or brace bars 19 may be shifted around to provide positive support for the die plate. After one hole has been drilled, the drill bushing 43 is removed and placed in another hole 28 of the punch plate and the procedure repeated until all of the die holes are formed in the die plate. These die holes will then be in perfect alignment with the punch holes in punch carrier plate 24, and the portion of the plate about these holes can be hardened without removing the plates from their supports by inserting a burner through the holes in the punch plate.

The die plate 13 may also be hardened by a flame 60 around the die holes (Fig. 7) by removing punch carrier plate 24 and applying the flame without removing the die plate from the supports. In order to confine the heat of the flame to the immediate vicinity of the hole 37, to avoid warping of the plate 13, a ring 61 of fire clay or other material may be arranged about the hole while the part within the ring is heated. Of course, the plate may be removed for hardening if desired.

50 By extending the brace bars 19 forward as at 50 in Fig. 2 a feeding ledge is provided on which the work-piece may be placed before inserting it into the apparatus.

If desired, the punch plate and die plate may 55 be held together by bolts 151 similar to the bolt 15 and while thus connected a die hole 37 may be bored therein and a companion preliminary hole 371 may be formed in the punch plate in alignment with the hole 37 by a drill 51. Thereafter the plates 13 and 24 are separated and each 60 of the preliminary holes 371 is enlarged to receive a punch guide sleeve or tube 27.

The construction described has the advantage 65 that in order to make a basic operating unit for any job, it is merely necessary to provide a die plate and a punch supporting plate, which plates are of relatively thin material and can be drilled and reamed as described and mounted on the side supports 12. These supports have the shoulders 14 and their upper bearing faces properly 70 spaced for supporting the two plates at a correct distance from each other and when a job is finished, the punch and die plates can be removed from the supports which can then be used for another set of punch and die plates. Since these

two plates are flat, they require no machining except the drilling and reaming of the holes, and they are, consequently, easily and economically made.

The method and apparatus described may be used in any case where a relatively large number of holes are required in a sheet of material, but are particularly desirable for many uses in airplane construction where it has been considered impractical to punch holes in plates because of the relatively high cost and time required to make the necessary hole punching dies. My improved apparatus can, however, be produced at a cost not more than the cost of drill jig-plates now commonly used for stack drilling the work, and once the apparatus is made, the work can be done at a rate of from ten to fifty times faster than drilling. My apparatus also effects a further economy in the use of drills, which are replaced in my apparatus by the use of punches of simple and inexpensive construction.

With the construction shown, a single set of plates may be provided with two or more series of holes for two or more different jobs, providing that the holes are so located in the two sets of plates that they do not overlap or interfere with each other. For example, there are two series of holes in the plates shown in Fig. 2, one series for use on the work-piece 38. The punch units are shown positioned in these holes. The same plates may be provided with additional holes 85 for use on another job. When the first job is being done, punch units are placed only into the holes of one series and when the second job is to be done by means of the same apparatus, all the punch and die units are removed from the first series of holes and are placed in the holes 85. This may require the use of other stop gages for positioning the work. In this manner, a number of different types of work can be produced by means of a single apparatus.

I claim as my invention:

1. A sheet material perforating apparatus comprising a base, spaced supports resting on said base, a die plate mounted on said supports in spaced relation to said base and provided with die openings, a punch plate mounted on said supports in spaced relation to said die plate and provided with guide openings in line with said die openings, guiding and stripping tubes arranged in said guide openings, punches slideable in said tubes and adapted to cooperate with said die openings, resilient means for raising said tubes relative to said punch plate, and resilient means for raising said punches relative to said tubes.

2. A sheet material perforating apparatus comprising a base, spaced supports resting on said base, a die plate mounted on said supports in spaced relation to said base and provided with die openings, a punch plate mounted on said supports in spaced relation to said die plate and provided with guide openings in line with said die openings, guiding and stripping tubes arranged in said guide openings, punches slideable in said tubes and adapted to cooperate with said die openings, resilient means for raising said tubes relative to said punch plate, resilient means for raising said punches relative to said tubes, and bracing means interposed between said die plate and said base.

3. A sheet material perforating apparatus comprising a base, spaced supports resting on said base, a die plate mounted on said supports in spaced relation to said base and provided with

die openings, a punch plate mounted on said supports in spaced relation to said die plate, punches slideable on said punch plate and adapted to cooperate with said die openings, resilient means for stripping said punches from the work, and bracing means interposed between said die plate and said base including a bar engaging its upper edge with the underside of said die plate and its lower edge with the upper side of said base and provided on its upper edge with recesses adapted to receive slugs from said die openings and discharge them laterally.

4. A sheet material perforating apparatus comprising a base, spaced supports resting on said base, a die plate mounted on said supports in spaced relation to said base and provided with die openings, a punch plate mounted on said supports in spaced relation to said die plate, punches slideable on said punch plate and adapted to cooperate with said die openings, resilient means for stripping said punches from the work, and bracing means interposed between said die plate and said base including a bar engaging its upper edge with the underside of said die plate and its lower edge with the upper side of said base and provided on its upper edge with recesses adapted to receive slugs from said die openings and discharge them laterally, said recesses being arranged in staggered relation on opposite sides of said bar.

5. A sheet material perforating apparatus comprising a base, spaced supports resting on said base, a die plate mounted on said supports in spaced relation to said base and provided with die openings, a punch plate mounted on said supports in spaced relation to said die plate, punches slideable on said punch plate and adapted to cooperate with said die openings, resilient means for stripping said punches from the work, and bracing means interposed between said die plate and said base including a bar engaging its upper edge with the underside of said die plate and its lower edge with the upper side of said base and provided on its upper edge with recesses adapted to receive slugs from said die openings and discharge them laterally, said recesses being arranged in staggered relation on opposite sides of said bar and each of said recesses having an inner inclined deflecting surface.

6. A sheet material perforating apparatus comprising a base, spaced supports resting on said base, a die plate mounted on said supports in spaced relation to said base and provided with die openings, a punch plate mounted on said supports in spaced relation to said die plate and provided with guide openings in line with said die openings, guiding and stripping tubes arranged in said guide openings, punches slideable in said tubes and adapted to cooperate with said die openings, resilient means for raising said tubes relative to said punch plate, resilient means for raising said punches relative to said tubes, and means for locating the work-piece to be perforated on the die plate.

7. A sheet material perforating apparatus comprising a base, spaced supports resting on said base, a die plate mounted on said supports in spaced relation to said base and provided with die openings, a punch plate mounted on said supports in spaced relation to said die plate, punches slideable on said punch plate and adapted to cooperate with said die openings, resilient means for stripping said punches from the work, and means for locating the work-piece to be per-

forated on the die plate including a brace bar secured to the base and engaging the underside of the die plate and provided with a locating pin adapted to engage with an opening in the work-piece.

8. A sheet material perforating apparatus comprising a base, spaced supports resting on said base, a die plate mounted on said supports in spaced relation to said base and provided with die openings, a punch plate mounted on said supports in spaced relation to said die plate and provided with guide openings in line with said die openings, guiding and stripping tubes arranged in said guide openings, punches slideable in said tubes and adapted to cooperate with said die openings, resilient means for raising said tubes relative to said punch plate, resilient means for raising said punches relative to said tubes, and means for locating the punch plate relative to the die plate.

9. A sheet material perforating apparatus comprising a base, spaced supports resting on said base, a die plate mounted on said supports in spaced relation to said base and provided with die openings, a punch plate mounted on said supports in spaced relation to said die plate and provided with guide openings in line with said die openings, guiding and stripping tubes arranged in said guide openings, punches slideable in said tubes and adapted to cooperate with said die openings, resilient means for raising said tubes relative to said punch plate, resilient means for raising said punches relative to said tubes, and means for locating the punch plate relative to the die plate including a plurality of locating pins adapted to be inserted into some of said guide openings and engaged at their ends with some of said die openings.

10. A sheet material perforating apparatus comprising a base, spaced supports resting on said base, a die plate mounted on said supports in spaced relation to said base and provided with die openings, a punch plate mounted on said supports in spaced relation to said die plate and provided with guide openings in line with said die openings, guiding and stripping tubes arranged in said guide openings, punches slideable in said tubes and adapted to cooperate with said die openings, resilient means for raising said tubes relative to said punch plate, resilient means for raising said punches relative to said tubes, and means for locating the punch plate relative to the die plate including a plurality of locating pins adapted to be inserted into some of said guide openings and having reduced tips engaging some of said die openings.

11. A sheet metal perforating apparatus comprising a base plate, spaced supporting rails secured thereon, each rail having a supporting surface on its top side and a rabbet on its inner side forming an intermediate upwardly facing shoulder, a die plate having its opposite edge portions secured to the shoulders of said rails and provided with integral die openings, a punch plate having its opposite edge portions secured to the top surfaces of said rails and provided with guide openings in line with said die openings, and punching units arranged in said guide openings and cooperating with said die openings.

12. A sheet metal perforating apparatus comprising a base plate, spaced supporting rails each secured with its underside to said base plate and having a supporting surface on its upper side and a rabbet on its inner side forming an intermediate upwardly facing shoulder, a die plate having its

opposite edge portions secured to the shoulders of said rails and provided with die openings, a punch plate having its opposite edge portions secured to the upper surfaces of said rails and provided with guide openings in line with said die openings, punching units arranged in said guide openings and cooperating with said die openings, and screws securing said die plate to said shoulders and accessible through openings in said punch plate.

13. A sheet perforating apparatus comprising a die plate having die openings, a punch plate arranged above the die plate and provided with guide openings in line with the die openings, and punching units each including a guiding and stripping sleeve slideable in one of said guide openings and adapted to engage its lower end with the top of the work-piece, means to allow the sleeve to slide and to raise it again, a punch slideable in said sleeve and adapted to cooperate with one of said die openings, and resilient means for raising said punch interposed between the upper end of said sleeve and a shoulder on said punch and including a plurality of alternating metal washers and rubber disks through which the punch passes.

14. An apparatus for punching a plurality of holes in sheets of material comprising a punch carrier plate provided with holes in accordance with which a counterpart is to be punched, punching units in said holes, and a die plate provided with apertures to cooperate with said punch units, said die plate being mounted in fixed spaced relation below said punch carrier plate in such manner that work placed between said plates will be punched when said punching units are properly actuated toward said die plate.

15. An apparatus for punching a plurality of holes in sheets of material comprising a punch carrier plate provided with holes in accordance with which a counterpart is to be punched, punching units in said holes, and a die plate provided with apertures to cooperate with said punch units, said die plate being mounted in fixed spaced relation below said punch carrier plate in such manner that work placed between said plates will be punched when said punching units are properly actuated toward said die plate, said die plate being supported in spaced relation to the bed of the press.

16. An apparatus for punching a plurality of holes in sheets of material comprising a punch carrier plate provided with holes in accordance with which a counterpart is to be punched, punching units in said holes, and a die plate provided with apertures to cooperate with said punch units, said die plate being mounted in fixed spaced relation below said punch carrier plate in such manner that work placed between said plates will be punched when said punching units are properly actuated toward said die plate, said die plate being supported in spaced relation to the bed of the press and being braced at intervals from the bed of the press by supports spaced clear of said die holes.

17. An apparatus according to claim 15 in which the die plate has only that portion of the plate in the immediate vicinity of each hole hardened.

18. An apparatus according to claim 15 in which the portions of the holes below the upper face of said plate are enlarged to facilitate the removal of slugs punched out of the work and in which only that portion of the plate in the immediate vicinity of each hole is hardened.

19. Perforating apparatus, including a pair of flat plates spaced apart and held in fixed relation to each other and having holes therein, punch units slidably mounted in the holes of one of said plates, the die holes in the other plate being of such size as to cooperate with punches of said punch units, each hole of one of said plates being in axial alinement with a hole of the other plate, whereby the punch units may move toward and into said holes in said plate to perforate the work positioned thereon.

20. A perforating apparatus, including a pair of flat plates spaced apart and held in fixed relation to each other and having holes therein, punch units slidably arranged in the holes of the upper of said plates, the holes in the lower of said plates being of a size to act as dies in cooperation with said punch units, each hole of one of said plates being in axial alinement with a hole in the other plate, whereby punches may be moved relatively to their plate into hole-punching relation to the other plate.

21. A sheet material perforating apparatus comprising spaced supports formed to rest upon the bed of a press, a die plate mounted on said supports in spaced relation to the lower ends thereof and provided with die holes in the plate itself, a punch carrier plate secured on said supports in fixed spaced relation to said base and having guide openings in alinement with the die openings of the die plate, individual punching and stripping units slidably mounted in the guide openings in said punch plate, whereby when work to be perforated is placed upon said die plate, the punches of said punching and stripping units will cooperate with the die holes to perforate the work.

22. A sheet material perforating apparatus, including a pair of plates provided with holes therein arranged according to the pattern of holes desired in the work, each hole of one plate being in axial alinement with a hole of the other plate, supports cooperating with the edge portions of said plates for supporting said plates, one above the other, in fixed spaced relation to each other, individual punching and stripping units slidably arranged in the holes of the upper plate, means for sliding said punch units upwardly to permit work to be placed between said plates and being slidably downwardly to perforate the work, the holes in the lower plate being formed to cooperate with the punch of said punching units for perforating the work.

23. A sheet metal perforating apparatus, comprising a base, upright supports at opposite edges of said base and each having shoulders below the upper faces thereof, a die plate supported on said shoulders in spaced relation to said base and having die holes formed directly therein, a second plate secured on the upper faces of said supports above and in spaced relation to said first-named plate and having holes therein, each hole being in axial alinement with a hole in the lower plate, punch units mounted in the holes of the upper plate and including punches adapted to penetrate work placed on said lower plate and enter into the die holes of the lower plate, said punches being of a size to fit the holes in said die plate itself.

24. A punch unit for use in a perforating device, said punch unit including a punch guide sleeve, a punch slidably lengthwise of said sleeve, a head for said punch, a resilient stripper member between said head and said sleeve, said punch unit including alternately arranged rubber disks

and rigid washers, for withdrawing the punch out of the work and into said sleeve, and means for supporting some of said washers above said head when said punch becomes shortened.

25. A punch unit for use in a perforating device, said punch unit including a punch guide sleeve, a punch slidably lengthwise of said sleeve, a head for said punch, a resilient stripper member between said head and said sleeve, said punch unit including alternately arranged rubber disks and rigid washers, for withdrawing the punch out of the work and into said sleeve, a portion of said punch extending through and above said head, and a cap on the upper end of said punch and having a hole to receive said portion of said punch, whereby a rigid washer may be removed from below said head to above said head and between said head and said washer to compensate for reduction in length of said punch.

26. A punch unit for use in a perforating device, said punch unit including a punch guide sleeve, a punch slidably lengthwise of said sleeve, a head for said punch, a resilient stripper member between said head and said sleeve, said punch unit including alternately arranged rubber disks and rigid washers, for withdrawing the punch out of the work and into said sleeve, a cap for said punch fitting over the head thereof and having a skirt portion into which said head may telescope, whereby when the punch becomes shortened, washers may be removed from below said head and placed between said head and said cap, to lower said punch in said sleeve and maintain the same overall length of said punch unit.

27. A perforating apparatus for use in a press, including supports formed to receive a punch unit carrier plate and a die plate secured in fixed spaced relation to each other, said punch carrier plate having holes therein arranged according to the pattern of holes required in the work, punch units arranged in said holes, said die plate having holes arranged therein so that each hole of one plate is in axial alinement with a hole of the other plate, and means for releasably securing said plates to said supports, so that said plates may be removed from said supports and replaced by other plates for operating on work of a different kind, said supports with said plates mounted thereon being insertable into and removable from a press without changing the positions of said plates relatively to each other.

28. A perforating apparatus according to claim 27, and including a base plate connecting said supports and spaced below said punch carrier plate and said die plate.

29. A perforating apparatus, according to claim 27 and including a T-slotted base plate on which said supports are removably mounted and on which said supports are adjustable toward and from each other to cooperate with plates of different widths.

30. A perforating apparatus, including a pair of flat plates spaced apart and held in fixed relation to each other and having holes therein, punch units slidably arranged in the holes of the upper of said plates, the holes in the lower of said plates being of a size to act as dies in cooperation with said punch units, each hole of one of said plates being in axial alinement with a hole in the other plate, whereby punches may be moved relatively to their plate into hole-punching relation to the other plate, and stop gages for the work on the lower of said plates.

31. A perforating apparatus, including a pair of flat plates spaced apart and held in fixed rela-

tion to each other and having holes therein, punch units slidably arranged in the holes of the upper of said plates, the holes in the lower of said plates being of a size to act as dies in cooperation with said punch units, each hole of one of said plates being in axial alinement with a hole in the other plate, whereby punches may be moved relatively to their plate into hole-punching relation to the other plate, stop gages for the work on the lower of said plates, and a sight hole in the upper plate through which a stop gage can be seen to facilitate positioning the work in correct relation to the stop gage.

32. A perforating apparatus including a punch carrier plate having a plurality of series of holes formed therein, each series of holes being arranged according to the holes required in a type of work, a die plate having corresponding series of die holes formed therein, supports to which said plates are secured in spaced relation one above the other, said supports holding said die plate above the lower surfaces of said supports, and a plurality of punch units formed to be placed into one series of holes at a time in axial alinement with die holes in the die plate, whereby the 25

same apparatus may be used for producing different types of work by placing punch units into different series of holes in said punch unit supporting plate.

5 33. An apparatus for punching a multiplicity of holes in sheet material including spaced plates fixed to end supports and carrying a multiplicity of slidable punches in concentric relation above cooperating die elements in the lower plate and 10 means for varying the lengths of said punch elements for maintaining the over-all length of each punch approximately the same as every other punch.

34. A punch unit for use in a perforating device, 15 said punch unit including a punch guide sleeve, a punch slidably lengthwise of said sleeve, resilient stripper means for retaining said punch in an elevated position relative to said sleeve for withdrawing the punch out of the work and into said sleeve, and means for varying the length of said punch unit for maintaining the overall length of said punch unit to compensate for unequal lengths of other punches in a group due to reductions in length which occur in servicing.

GEORGE F. WALES.
